BACK REST FOR CHAIRS

John S. Burdick, North Muskegon, Mich., assignor
to The Shaw-Walker Company, Muskegon,
Mich., a corporation of Michigan

Application September 26, 1950, Serial No. 186,812

3 Claims. (Cl. 155—191)

1

This invention relates to improvements in chairs, and more particularly to the back rest or back splat portion of chairs.

The principal object of the invention is to provide an improved form of back rest or back splat unit adapted for chairs having a generally upright back frame in which the lower edge of the back rest is spaced a few inches above the level of the rear edge of the seat and is flared rearwardly of said seat so as to afford maximum comfort in and below the lumbar region of an average person occupying the chair.

As heretofore constructed in conventional back rest design, it has been customary to provide a plurality of back splats extending downwardly from the top rail of the back frame to a horizontal cross bar, with the back splats curved in a vertical plane toward the front of the splat unit and with the cross bar curved toward the rear of the unit. The cross bar has been placed at various levels above the seat of the chair, but it has been customary to form the cross bar with a substantially uniform cross section throughout its length and with its front face disposed in substantially the same upright angle as the side rails of the back frame to which the opposite ends of said cross bar are connected. Since in most chair designs the side frame of the back rest is usually slanted slightly toward the rear, the front face of the cross bar usually assumes substantially the same upward and rearward slant throughout the entire length of the cross bar. As a result, the cross bar presents a relatively sharp lower edge which is uncomfortable to the occupant.

In carrying out my invention, I provide an improved form of back rest unit including a back rest area curved in vertical planes toward the front thereof and terminating in a cross bar of substantially uniform cross sectional area curved rearwardly between the side rails of the back frame, wherein said cross bar is of novel form consisting of end portions having front and rear surfaces substantially in vertical alignment with the side rails of the back frame, but with said surfaces assuming a reversed slanting direction across the center of the bar for a major portion of its length, so that said cross bar forms a rearwardly flaring continuation of the convex back rest area of the back splat unit.

The invention may best be understood by reference to the accompanying drawings, in which like numerals apply to like parts in each of the figures:

Figure 1 is a front view of a chair constructed in accordance with my invention;

2

Figure 2 is a top plan view of the chair shown in Figure 1;

Figure 3 is a side view of the chair;

Figure 4 is a fragmentary side view of the chair shown in the foregoing figures with the lower portion of the back splat unit shown in section, and indicating the normal relation of the back splat unit to the back of an average occupant of the chair;

10 Figure 5 is an enlarged detailed perspective sectional view of the back rail taken on line 5—5 of Figure 1;

Figure 6 is an enlarged detailed top plan view of the novel form of cross bar forming part of my invention;

Figure 7 is a front view of the bar shown in Figure 6;

Figure 8 is an end view of the bar shown in Figure 6;

20 Figure 9 is a bottom view of the rail shown in Figure 6.

Referring now to the details of the embodiment of my invention illustrated in the drawings, the chair shown in Figures 1 to 4, inclusive, for illustrative purposes is an arm chair of the type commonly employed in business offices, including as its principal elements a back frame 10, a seat 11, front legs 12, 12, rear legs 13, 13 and arm rests 14, 14. The back frame includes 25 upright side rails 16, 16 filled in by a back splat unit indicated generally at 17, having a plurality of upright splats 18 secured at their upper ends to the top rail 15 and at their lower ends to a cross bar 19.

30 The parts hereinabove described may be made of wood, tubular metal or any like material, or a combination of both wood and metal, although it is usually preferable that the back splat unit, the seat and the arm rests be made of wood or other non-metallic material, in order to avoid bodily discomfort of the occupant by contact with metal parts which tend to give a chilling sensation at relatively low temperatures.

35 Referring now to details of the form and construction of the back splat unit 17, the splats 18 are curved in a vertical plane toward the front of the chair, the degree of curve increasing in abruptness as the splates approach the cross bar 19, to form a back rest area conforming generally 40 to the shape of the average occupant's back at the lumbar region, when the occupant is sitting in a generally upright position, as indicated in Fig. 4. Said cross bar is disposed substantially above the top level of the seat 11, in the form shown herein 45 this vertical distance being approximately three

or four inches. Although this distance may vary somewhat, the cross bar is preferably spaced vertically above the level of the seat to be substantially across the sacroiliac region of the average occupant and above the coccyx when the occupant is in a generally upright seated position, as shown.

Referring now in greater detail to the novel shape of the cross bar 19 as shown in Figures 6 to 9 inclusive, the opposite end faces 20, 20 of said bar are formed in the shape of a substantially equal sided parallelogram excepting that the front upright face 21 may be slightly shorter than the rear face 22 of the bar adjacent its opposite ends. The front and rear faces meet the end face 20 at each end of the bar along upwardly and rearwardly inclined edges 23 and 24, which are substantially parallel with the side rail 16 of the back frame, but the front and rear faces quickly assume a reversely inclined position as they progress toward the center of the cross bar so that the major portion of said cross bar has a front face portion 26 and a rear face portion 27 both inclined downwardly and rearwardly with respect to the longitudinal axis of said cross bar, with the greatest degree of rearward flare along the center of said bar. The upper face of the cross bar remains at a slight forward slant throughout the length of the bar, which is substantially normal to the splats which are secured thereto. The bottom face 29 remains in a substantially horizontal plane, as shown in Figures 5 to 9.

The cross bar 19 can be readily shaped in the special form shown and described in any conventional shaping machine.

The forwardly curved back splats 18 have their lower ends suitably secured as by mortise and tenon connections 30, 31 along the top of the cross bar so that the front faces of said back splats at their lower rearwardly curved ends are disposed closely adjacent the rearwardly flaring central front face portion 26 of the cross bar, so that the latter bar forms a substantial continuation of said convex rearwardly flaring back rest area, terminating substantially above and to the rear of the seat 11.

With my novel form of cross bar 19 having its front and rear surfaces tapered to conform generally with the lines of the side rails 16 but with these surfaces changed in a direction toward and along the major portion of the bar, substantially in line with the curvature of the back splats, ample clearance is provided at the height of the cross bar above and rearwardly of the seat so as to relieve any discomforting pressure on the lower part of the spine of an occupant when normally seated in upright position in the chair. In particular it will be noted that, when the occupant sits well backward in the seat, the rearwardly and downwardly flared portion of the back rest gives positive support to the lower lumbar and sacroiliac region tending to induce the occupant to assume the ideal erect seated position with the spine arched naturally in the lumbar and sacroiliac region.

Accordingly, this novel form of back splat unit therefore combines maximum comfort to the

user, with a particularly pleasing and effective streamlining effect and a maximum strength and minimum amount of material required for the cross bar 19.

Although I have shown and described a certain embodiment of my invention, it will be understood that I do not wish to be limited to the exact construction shown and described, but that various changes and modifications may be made without departure from the spirit and scope of the invention as defined in the appended claims.

It will be further understood that, although my invention has been shown and described in connection with a back rest formed of back splats, the novel form of cross bar shown and described can equally well be employed with other types of back rest means, such as wood, metal, plastic or upholstered back rest units, if desired.

I claim:

20. 1. In a chair, a back frame and seat, the back frame comprising a top rail and side rails connected to the seat and a back splat assembly comprising a generally horizontal rearwardly curved cross bar having its opposite ends connected to the side rails so as to extend substantially across the sacroiliac region and above the coccyx of an average occupant of the seat, and a plurality of spaced upright splats extending between and fixed to said cross bar and top rail, said back splats being curved in a vertical plane to present a downwardly and rearwardly flaring back rest area along its lower margin, the opposite ends of said cross bar being joined to the side rails with its front and rear surfaces in substantial parallel 35 upright alignment therewith, but the plane of the front face of said cross bar being gradually twisted intermediate its ends to present a downwardly and rearwardly flared surface along its central portion at angles corresponding substantially to the adjacent portions of said downwardly and rearwardly flaring back rest portions, and said cross bar being of substantially uniform cross-sectional area throughout its length.

40. 2. A chair structure in accordance with claim 1, 45 wherein the rear surface of said cross bar is substantially parallel with the front surface thereof throughout the length of said cross bar.

45. 3. A chair structure in accordance with claim 2, 50 wherein the upper surface of said bar is disposed at a forward slant throughout its length substantially normal to the splats which are secured thereto.

JOHN S. BURDICK.
